UNITED STATES PATENT OFFICE.

FRANK B. WIDMAYER, OF NEW YORK, N. Y.

ELECTRIC IRON.

1,409,131.

Specification of Letters Patent.

Patented Mar. 7, 1922.

Application filed November 20, 1920. Serial No. 425,410.

To all whom it may concern:

Be it known that I, FRANK B. WIDMAYER, a citizen of the United States, and a resident of the city of New York, borough of Manhattan, in the county and State of New York, have invented a new and Improved Electric Iron, of which the following is a full, clear, and exact description.

This invention relates to electric irons and has for an object to provide an electric iron which is capable of a wide variety of usage.

Another object resides in the provision of means whereby by the assemblage of a plurality of simple elements or sections irons of different weights and sizes may be provided.

A further object resides in the provision of means whereby the various sections when assembled are rigidly and compactly aligned and interlocked.

20 A still further object resides in the provision of means whereby the electric heating sections of the adjacent sections are automatically interconnected when the mechanical connection between the sections is established.

Another object resides in the particular construction and arrangement of parts hereinafter described and claimed and shown in the accompanying drawings.

30 A further object of my invention comprises an electric iron constructed so that if any particular heating element burns out it is not necessary to install a new complete element or unit but it is only necessary to replace that particular element or section which is burned out.

A still further object of my invention is to provide an electric iron constructed so that each unit or electric element section can be connected electrically to a switch or plug on the top body of the iron so that it may be cut in or out to regulate the heat.

It is to be understood that I do not limit myself to the exact mechanical or electrical details of construction herein shown, since modifications in the same can be made without departing from the spirit of the invention.

The invention is illustrated in the drawings, of which—

Figure 1 is a perspective view of the iron when only one section is used;

Figure 2 illustrates the form of iron when two sections are used;

55 Figure 3 is a horizontal section taken through the iron showing the heating ele-

ments and the manner of interconnecting the sections both mechanically and electrically;

Figure 4 is a transverse vertical section showing how the handle interlocks with the body of the sections;

Figure 5 is a horizontal section through the iron showing a modified form of connecting means for the sections; and

Figure 6 represents a modified form of iron in which an auxiliary bottom plate can be attached to the ordinary ironing surface.

As shown in the drawings the invention comprises a plurality of sections 1 and 2 having ironing faces 3 and 4 and vertical end faces 5 and 6 which are adapted when the sections 1 and 2 are used together to abut each other. Within the sections 1 and 2 suitable heater elements 7 and 8 are disposed and packed therein in any suitable manner. The ends of element 7 are connected to suitable conducting pins 9 and 10 mounted in insulating bushings 11 and 12 which are threaded into apertures in the end wall 6 of section 1. The ends of the pins 9 and 10 extend beyond the edge of the wall 6. The ends of the heater element 8 in section 2 are connected to conducting rods 13 and 14. At one end these conducting rods pass through insulating bushings 16 and 15 and extend beyond the rear wall of the section 2 to engage with any suitable type of terminal plug 17. The other ends of the conducting rods 13 and 14 are adapted to 90 contact and be seated in suitable bores in conducting sleeves 18 and 19, which are in turn seated in insulating plugs 20 and 21 disposed in the face 5 of section 2.

When the sections 1 and 2 are placed with the edges 5 and 6 abutting each other the ironing surfaces 3 and 4 are adapted to lie in perfect alignment to form one continuous ironing surface. To effect this perfect alignment I provide suitable metallic socket portions 22 and 23 in the abutting edges 5 and 6 of sections 1 and 2, into which pins 24 and 25 mounted on the respective sections extend to interlock and connect the sections together. When the sections are thus brought together the pins 9 and 10 extend into sleeves 18 and 19 to make and complete the electrical circuit for the heating elements 7. The weights of sections 1 and 2 are so designed that if section 1 is used alone, as shown in Figure 1, an iron adaptable for ironing light pieces is formed,

105

110

whereas if the section 2 is connected to section 1 a heavier iron is formed. From the upper face of each section a suitable threaded stud or pin 26 is adapted to extend, on 5 which a thumb nut 27 may be fastened to hold a handle portion 28 to the body of the iron. The base portion 29 of the handle 28 is adapted to be seated in a slot portion 30 extending longitudinally along the upper 10 face of the section 1 and the section 2. When the plurality of sections are used together the handle portion, of course, is longer, as shown in Figure 2, in the base portion 31, which likewise extends into a 15 groove similar to the groove 30 and is fastened thereon by the same sort of means. The provision of this groove in the upper face of the section and the engagement therewith of the handle portion furnishes 20 additional means whereby the section can be rigidly locked together in alignment.

As shown in Figure 5 I may provide threaded apertures in the rear wall 6 of section 1 into which bolts 32 and 33 may extend. These bolts, which have thumb screws 25 on their ends, extend from the rear face of section 2 and therethrough into the above mentioned threaded socket. These bolts may also serve to hold the connecting plug 17 30 to the body of the iron, as well as the auxiliary or false bottom plate shown in Figure 6. This particular construction is shown in Figure 5.

In order to obtain an extra smooth and 35 fine ironing surface for especially fine lace, I can provide an auxiliary or false bottom as shown in Figure 6. This bottom plate 34 can be made out of pressed iron or steel, highly polished and nickelized and shaped to 40 fit the iron bottom. The front end 35 of this plate is upturned to fit the forward portion, as shown at 37, and the rear end is upturned to engage the rear face of the iron, as shown at 38. The rear end 38 is provided with 45 holes 36 through which the stud bolts 32 and 33 may extend to hold the plate in place.

I claim:

1. An electric iron comprising a plurality of sections having ironing surfaces adapted 50 to be connected together to form a continuous ironing surface.

2. An electric iron comprising a plurality of sections, ironing surfaces on each section, heating elements in each section, means to 55 connect the sections together whereby a continuous ironing surface is formed, and means to establish the electric circuit automatically when the mechanical connection is made.

3. An electric iron comprising a plurality 60 of sections adapted to be connected together, ironing surfaces on each section adapted when connected to form a continuous sur-

face, the upper surfaces of the sections being provided with grooves which align when the sections are connected, a handle having a 65 base portion adapted to lie in the aligned grooves, and means for fastening the handle to the sections.

4. An electric iron comprising a plurality of sections having ironing surfaces adapted 70 to be connected together to form a continuous surface, and means on the abutting surfaces to mechanically and electrically connect the sections.

5. An electric iron comprising a plurality 75 of sections having ironing surfaces, means on the abutting faces of the sections adapted to mechanically and electrically connect the sections, a handle adapted to be fastened to the outer faces of the section, and means on 80 the body portion co-operating with the handle to align the sections.

6. An electric iron comprising a plurality of sections having ironing surfaces, a handle adapted to be fastened to the sections, and 85 means on the body of each section adapted to co-operate with the handle to align the sections.

7. An electric iron comprising a plurality 90 of sections having ironing surfaces, adjacent faces adapted to abut each other when the sections are connected, said adjacent faces having sockets therein, pins on the adjacent faces adapted mechanically to lock with the socket to align the sections, heating elements 95 in each section, and plug and socket connections in the adjacent ends to connect the elements electrically when the sections are placed adjacent each other.

8. An electric heating iron comprising a 100 plurality of ironing sections, means for mechanically and electrically connecting the sections together, an auxiliary or false bottom plate adapted to be attached to the bottom surface of the section, and means for 105 connecting the plate to the body portion of the iron.

9. An electric heating iron comprising a plurality of sections having ironing surfaces, means on abutting faces of the sections 110 to mechanically and electrically connect the sections, an auxiliary sheet metal plate adapted to form an ironing surface, means for attaching said plate to the ironing surface of each section, a handle adapted to be 115 fastened to the top or outer surface of the section, and means on the body portion co-operating with the handle, with the connecting means and with the auxiliary ironing surface to align the sections.

FRANK B. WIDMAYER.
